UNITED STATES PATENT OFFICE.

JOHN JOHNSON, OF CHICAGO, ILLINOIS, ASSIGNOR OF ONE-HALF TO CHARLES F. McQUAID,
OF CHICAGO, ILLINOIS.

WRENCH.

No. 894,208.

Specification of Letters Patent.

Patented July 28, 1908.

Application filed August 21, 1907. Serial No. 389,469.

To all whom it may concern:

Be it known that I, JOHN JOHNSON, a citizen of the United States, and a resident of the city of Chicago, in the county of Cook and 5 the State of Illinois, have invented certain new and useful Improvements in Wrenches, of which the following is a specification.

My invention relates to that class of wrenches which are especially adapted for 10 use at different angles or amid such obstructions as preclude free action, and my invention resides in the novel construction as set forth hereinafter.

In the drawings, Figure 1, is an elevation 15 of my wrench showing the internal mechanism in dotted lines. Fig. 2, is a sectional view of Fig. 1 taken through the line A B of Fig. 1: Figs. 3 and 4 represent two different forms of wrench heads used in my device.

20 More particularly described C represents the handle of my wrench, which is adapted to be removably connected with the body of the wrench, and threaded at the end G to engage with said body, and is tapered for the purpose of effecting a tight joint with said body. The said body consists of a tubular cross arm F, which is fitted interiorly with opposingly notched lines of ratchets f and f', and engaging the said cross arm F, at its either end are 25 the tubes M and M' which at their inner ends K are notched to correspond in size and position with the ratchets f and f' respectively.

30 Across the diameter of the tubes M and M' are fitted the pins H H which are perforated in opposition to each other. A link I lies within the cross arm F and is hinged at its opposite sides to the pins J J which pass through the said suitable perforations in the pins H H and are spring seated thereupon 35 as shown at E. The action of the springs E upon the pins J J serves to draw the tubes M and M' toward each other, holding them in engagement with the ratchets f and f'.

40 Wrench heads L L, constructed of tubular metal and fitted at one end in form to suitably embrace the nut to be acted upon, are slotted at the opposite end in form to suitably embrace the pins H H when the said wrench head is telescoped into the tubes M and M' 45 respectively.

In operation the wrench is so constructed that when the wrench head L is inserted in the tube M, the handle of the wrench is thrust to the right to act upon the nut engag-

ing the wrench, and when thrust to the left 55 the ratchets f slip upon the notches K of the tube M.

When the wrench head is inserted in the tube M' the ratchets f' are engaged upon the handle being thrust to the left and slipped 60 upon the notched end K of the tube M' when the handle is thrust to the right.

Any form of connecting pins H H may be used which may seem mechanically desirable, and any other means of normally holding tubes M and M' in contact with the ratchets f and f' may be used.

My wrench heads I expect to make of any desirable size, form and number.

What I claim as my invention is:

1. A wrench consisting of a handle and a body, said handle being adapted to engage by a screw thread and a taper formation the said body at right angles, said body comprising a tube fitted interiorly with two lines of ratchets 75 opposingly cut in reference to each other, smaller parallel tubes telescoping within said larger tube and so cut upon the inner edges as to correspond with and engage the said ratchets, wrench heads adapted to engage 80 the outer ends of the said smaller tubes which are held normally in contact with the said ratchets.

2. A wrench consisting of a handle and a body engaging each other in the form of a 85 letter T, said body comprising a tube perforated to receive the said handle in engagement, a plurality of parallel lines of ratchets opposingly cut in relation to each other, fitted within said tube and running at right 90 angles to the length of said tube, smaller tubes telescoping within the said larger tube and cut at their inner ends to correspond with the said lines of ratchets, wrench heads fitted within the outer ends of the said 95 smaller tubes with means whereby said smaller tubes are held normally in engagement with the said ratchets consisting of spring seated pins engaging the smaller tubes respectively, and means whereby the said 100 spring seated pins are connected with each other.

3. A wrench consisting of a handle and a body engaging each other in the form of a letter T, the said body consisting of a tube 105 fitted interiorly with two lines of ratchets opposingly cut with reference to each other, smaller tubes telescoping within each end of

said body tube, fitted on their inner ends with ratchets corresponding with the ratchets in said body tube, cross pins fitted within the said smaller tubes and adapted to engage gage wrench heads fitted in the outer ends of the said smaller tubes and means whereby said smaller tubes are normally held in en-

gagement with the said ratchets of the said body tube.

JOHN JOHNSON.
